UNITED STATES PATENT OFFICE

ROLAN JAY WIGHTMAN AND WILLIAM ASTLE, OF LITTLE FALLS, NEW YORK, AS
SIGNORS TO CHERRY-BURRELL CORPORATION, OF LITTLE FALLS, NEW YORK

HEAT EXCHANGE APPARATUS

Application filed July 24, 1929. Serial No. 380,582.

This invention relates to heat exchange apparatus of that kind which comprise a bank or group of tubes connected end to end to form a continuous flow passage for a fluid for the purpose of an exchange of heat between the fluid within the passage and the fluid or medium contacting with the exterior of the tubes. More particularly the invention is directed to improvements in apparatus of this sort adapted for use as a regenerator in the pasteurization of milk and other liquids, and in which the cold liquid to be pasteurized and the warm pasteurized liquid flow, the one through, and the other over the external surfaces of, the tubes for raising the temperature of the cold liquid and reducing the temperature of the warm liquid.

In this type of heat exchange apparatus the headers and return caps or connectors which join the tubes end to end, are usually soldered, brazed or otherwise rigidly joined to the tubes. It has been found by experience that there are certain disadvantages to such rigid construction. In the usual operation of such apparatus, the cold liquid at a temperature, say approximately 40 degrees, is discharged on the outer surface of the uppermost tube and flows down over the outside surfaces of the tubes, while the pasteurized or hot liquid is delivered to and enters the inside of the lowermost tube at a much higher temperature, for instance, approximately 145 degrees. There is a heat exchange of about 80 percent, the cold liquid being heated to about 125 degrees, and the hot liquid being cooled to about 60 degrees. These widely different temperatures affecting different parts of the device produce uneven expansion and contraction of the tubes, which places severe strains on the joints. Even greater strains are occasioned during the sterilization of the apparatus, in which steam may be passed through the tubes, and hot water at 180 degrees or more may be run over the exterior of the tubes. Experience has shown that unless this sterilization is done very carefully by gradually heating up the tubes, the solder joints are liable to crack loose or, in case the joints are brazed or the solder joints hold, the tubes are liable to spring or bow out of proper

alignment and interfere with the uniform and efficient operation of the apparatus.

One object of our invention is to provide a heat exchange apparatus of the type mentioned which is of a practical and desirable construction such as to avoid the above mentioned objections.

Other objects of the invention are to leave the tubes unsecured except at their mid-length portions only so as to permit free and independent expansion and contraction of the tubes at their opposite ends; also to construct the apparatus so that while leaving the ends of the tubes free to expand and contract lengthwise, they nevertheless will be retained in proper alignment and spacing so as to preserve the predetermined relation or position of the tubes necessary to the uniform flow of the liquid over the surfaces of the tubes; also to support the tubes and connect the tubes end to end so as to permit independent expansion and contraction of the ends of the tubes relatively to each other and to their supports, and the return caps or connectors at the ends of the tubes; also to provide return caps or connectors for the ends of the tubes which are attached to the tubes by liquid tight joints which nevertheless allow the necessary slightly different movements of the tubes relative to the return caps or connectors, caused by the differential expansion and contraction of the tubes; also to provide the apparatus with side and top closure members which form an enclosing chamber for the tubes or heat exchange parts, but which are readily movable to expose or afford access to the tubes; also to provide a combined base and liquid trough which forms the support for the apparatus and avoids the necessity for the usual outside frame-work, supporting pipes, etc; and also to improve heat exchange apparatus in the other respects hereinafter described and set forth in the claims.

In the accompanying drawings:

Fig. 1 is a side elevation of a heat exchange apparatus embodying the invention showing portions of the side closure members and the bottom trough broken away and one section of the top cover raised out of its closed position.

- Fig. 2 is an end elevation of the apparatus on an enlarged scale.
- Fig. 3 is an enlarged, transverse, sectional elevation thereof on line 3—3, Fig. 1.
- 5 Fig. 4 is a fragmentary, longitudinal sectional elevation thereof on a still larger scale.
- Fig. 5 is a sectional elevation of the body member of one of the tube connectors or return caps.
- 10 Fig. 6 is a transverse, sectional elevation of the apparatus, on an enlarged scale, on line 6—6, Fig. 1.
- Fig. 7 is a fragmentary, inside elevation of one of the transverse track bars of the apparatus.
- 15 Fig. 8 is a transverse, sectional elevation of the liquid distributor.
- Fig. 9 is a transverse, sectional elevation of one of the removable cover sections.
- 20 Fig. 10 is a fragmentary plan view thereof.
- The apparatus may be made in one or more sections, the apparatus illustrated in the drawings being composed of three similar sections A, B and C, arranged one upon another. Each section comprises a bank or series of tubes 11 arranged side by side, preferably horizontally one above another and joined end to end in series by return caps or connectors 12, and in the case of a multiple section apparatus, the adjacent tubes of adjacent sections are similarly connected so as to form a continuous zig-zag flow passage for the liquid. Preferably, the tubes of each section are rigidly secured in proper spaced relation at their mid-length portions, or between their ends, by upright braces 13 which may be conveniently made in two halves recessed to fit and embrace the opposite sides of the tubes, the two halves of the brace being rigidly secured to the tubes and to each other between the tubes as by brazing or soldering. The opposite ends of the tubes are loosely supported, preferably by passing through holes 14 in vertical supports or end members 15, the holes 14 being sufficiently large to permit the tubes to be passed through and to move in the holes in the lengthwise expansion and contraction of the tubes.
- 40 The return caps or connectors 12 which join the tubes end to end are coupled to the ends of the tubes in a manner to form liquid tight joints between the tubes and connectors, but nevertheless permit the slight movement of the tubes in the connectors incident to the differential expansion and contraction of the adjacent tubes, and preferably to also permit the connectors to be readily disconnected from the ends of the tubes. In the preferred construction shown, see Figs. 4 and 5, each of the connectors comprises an annular body 16 which is secured to the ends of two adjacent tubes, and a cap 17 hinged to the body. The body 16 is provided with two threaded holes 18 in each of which the end of one of the tubes 11 is clamped by a screw ring 19 which surrounds the tube and is screwed into the threaded hole 18 so as to engage a tapered packing ring of brass or other suitable metal 20 surrounding the tube at the inner end of the screw ring. By screwing in the screw rings 19, the packing rings 20 are wedged in between the tubes and the tapered inner ends of the holes in the body 16. The packing rings 20 are of slightly less taper than the cooperating seats in the holes 18 and form liquid tight joints between the ends of the tubes and the body of the connector. The cap 17 is preferably pivoted on an arm 21 hinged to the body 16 at one side thereof at 22, and the cap is adapted to be clamped against the outer edge of the body, for instance by a screw 23 hinged to the opposite side of the body and adapted to swing between the legs of the forked, free end of the hinge arm 21, the screw carrying a wing nut 25 adapted to bear against the forked end of the arm for forcing the cap towards the body. A packing gasket 26 of paper or other suitable material encircling the inner end of the cap between a shoulder thereon and the outer edge of the body 16 insures a liquid tight joint between the cap and the body.
- 45 By the construction described, the ends of the tubes 11 are free to move endwise independently in the holes 14 in the end supports 15 under the expansion and contraction of the tubes, and the couplings between the connectors and tubes enable the slight relative movement of the tubes and connectors which may be caused by reason of a difference in expansion and contraction between the ends of the two tubes which are joined by a connector. This movement, due to differential expansion and contraction in adjacent tubes, at most, will be very slight.
- 50 The end supports 15 of the second section B rest upon the end supports of the bottom section A of the apparatus, and may be secured thereto as by bolts 30 passing through the abutting ends of the end supports, and the end supports of the top section C similarly rest on and are bolted to the end supports of the second section B. The bottom section A rests upon and is secured as by bolts 31, to a combined base and liquid trough which is preferably built up of upright end pieces or castings 32 and 33 connected by longitudinal brace and tie rods 34, and upper side bars 35 which support the trough 36 extending lengthwise beneath the lowermost tube of the bottom section of the apparatus. The side bars 35 are preferably angle bars arranged at an angle to the vertical, as clearly shown in Fig. 3, and the upwardly diverging sides of the trough, which may be formed of sheet metal, bear upon the inclined upper flanges of the bars 35, with the side edges of the trough sheet bent over and soldered or brazed to the upper flanges of the angle bars. One end of the
- 55 60 65 70 75 80 85 90 95 100 105 110 115 120 125 130

trough rests upon and is secured to a flange 37 on the end casting 32 of the base and the opposite end of the trough rests upon and is secured to a similar flange 37a on the opposite end casting 33 of the base, said flanges conforming to the cross sectional form of the trough. The end castings 32, 33 form the ends of the trough, which is shallow, and the end casing 33 is preferably formed with a pocket 38, see Fig. 4, which is deeper than the lower end of the trough 36 and is adapted to receive the liquid draining out of the trough whereby the liquid collects to a sufficient depth in the pocket to keep the pump inlet pipe 39 always submerged notwithstanding that there need be only a very shallow stream of liquid in the trough. The purpose of this shallow bottom trough is to prevent milk from collecting therein in quantity and being held a considerable time at an undesirable temperature, and to prevent the formation of a scum or foam which is liable to run high in bacterial count, which is an objection to the usual deep trough holding a body of milk of considerable depth.

As usual in liquid heat exchange devices of this type, the liquid is discharged on the uppermost tube 11 of the apparatus from a suitable distributor 41 adapted to uniformly distribute the liquid in a thin film over the surface of the uppermost tube. The distributor shown is constructed and operates as described in the application for United States Patent Serial No. 174,922, filed March 12, 1927, but it could be of any other suitable construction. The distributor shown is provided at its middle with an inlet fitting 42, Figs. 4 and 8, which is recessed at its bottom at 43, and is adapted to straddle and rest upon the upper end of the center brace 13 of the top section C of the apparatus, and at its opposite ends the distributor 41 is provided with end pieces 44 adapted to enter and rest in seats or notches 45, see Figs. 4 and 7, in transverse top bars or tracks 46, which are rigidly secured on the top ends of the end supports 15 of the top section of the apparatus. The top track bars 46 are preferably of the channel form shown in Fig. 4 and constitute tracks for the supporting wheels of the side closure plates for the apparatus.

The tubes are provided with the usual bottom ribs 47 for ensuring the proper flow of the liquid from one tube to the next lower tube, and preferably the tubes are equipped with inclined overlapping collars or circumferential dams 48 adjacent the end supports 15 to keep the liquid from contact with the end supports.

50 and 51 represent upright side covers or walls which are movably supported at opposite sides of the bank of tubes, and in conjunction with the trough base and a top cover form a protecting enclosure for the

heat exchange elements. These side walls may be of any suitable construction, but as shown, consist of rectangular angle bar frames 52 to which sheet metal plates 53 are secured at their edges, the walls being 70 braced and stiffened by vertical brace rods 54 connecting the top and bottom frame bars. Each side wall or cover 50—51 is provided at its top at opposite ends with wheels 55 adapted to roll on the tracks 46, the side wall being hung by suitable journal brackets 56 from the wheels, whereby the wall is adapted to move freely toward and from the sides of the bank of tubes. The walls or covers 50, 51, extend from one to the other of the end supports 15 for the tubes and are adapted to be secured against the outer faces of the end members by suitable means, such as latches 57, see Fig. 2, to thereby effectually close in the opposite sides of the heat exchange tubes.

The top cover or roof shown is formed in two sections 60 and 61, which are adapted to be placed over the distributor at the top of the apparatus and cover the same from one to the other of the transverse track bar 46. Each cover section shown is provided at its outer end with a depending notched flange 62 adapted to rest upon studs or pins 63 projecting inwardly from the upturned, inner edge of the bottom flange of one of the transverse track bars 46, and at its inner end is provided with similar notched flanges 64 which are adapted to rest on pins or studs 65, see Figs. 1 and 8, projecting from the middle fitting 42 of the liquid distributor 41. The cover sections 60 and 61 are notched at their inner ends at 66, see Fig. 10, to fit against the upright nipple of the center fitting 42, and are preferably provided with suitable handles 67 for lifting them. When the top cover sections are in position, resting on the transverse track bars 46 and on the center fitting of the distributor, they extend over the top of the distributor and heat exchange tubes 11 from one to the other of the track bars 46 and from the upper edge of one of the side covers 50 to the upper edge of the other side cover 51, and effectually enclose the upper portion of the apparatus. The bottom edges of the side covers when in closed position, extend close to the side edges of the base trough 36 so that the trough, side covers and top cover form a complete chamber effectually enclosing the heat exchange tubes and distributor and protect the liquid flowing on the exterior of the tubes from contamination. Nevertheless the side covers can be easily rolled away from the bank of tubes, and the top cover readily removed to expose or afford access to the bank of tubes when this is necessary, for cleaning the apparatus or for other reasons.

We claim as our invention:

1. In a heat exchange apparatus, the com-

bination of a series of tubes arranged side by side and connected end to end in series, means which hold the tubes and maintain the relative position thereof but which leave the ends of adjacent tubes free to expand and contract lengthwise independently of each other and relatively to their end connections, and means for holding the ends of the tubes against displacement in a direction at an angle to their length.

2. In a heat exchange apparatus, the combination of a series of tubes arranged side by side, means for securing the tubes at their mid-length portions, means whereby the relative position of the tubes is maintained while the tubes are left free to expand and contract lengthwise, and connectors which join said tubes end to end in series and are coupled to the tubes so as to permit independent movement of the ends of the tubes relative to the connectors.

3. In a heat exchange apparatus, the combination of a series of tubes arranged side by side and connected end to end in series, means securing the tubes between their ends, and supports for holding the ends of the tubes in predetermined relation, the ends of the tubes being free to expand and contract lengthwise independently relatively to said end supports and relatively to their end connections.

4. In a heat exchange apparatus, the combination of a series of substantially horizontal tubes arranged one above another and connected end to end in series, means securing said tubes at their mid-length portions, and end supports for the opposite ends of the tubes, the ends of the tubes being loosely supported and held in place by said end supports while being free to expand and contract lengthwise independently relatively to each other and to their end connections.

5. In a heat exchange apparatus, the combination of a series of tubes arranged side by side, means securing said tubes at their mid-length portions, supports by which the ends of the tubes are loosely supported so as to leave the tubes free to expand and contract lengthwise independently, and connectors joining said tubes in series, said connectors being connected to the tubes by liquid tight joints which permit slight independent expansion and contraction of the ends of the tubes relative to the connectors.

6. In a heat exchange apparatus, the combination of a series of tubes arranged side by side, end supports provided with seats in which said tubes are loosely held, whereby the relative position of the tubes is maintained, but the tubes are free to expand and contract lengthwise independently, and connectors joining said tubes end to end in series, said connectors being connected to said tubes by liquid tight joints which permit slight

independent movement of the tubes relative to the connectors.

7. In a heat exchange apparatus, the combination of a combined supporting base and trough comprising cast metal trough ends and a sheet metal trough body secured to said ends and together therewith forming a trough, end supports secured on and rising from the trough ends, and a bank of tubes supported one above another lengthwise over said trough by said end supports, whereby the heat exchange apparatus is supported by said trough base.

8. In a heat exchange apparatus, the combination of a base comprising rigid end pieces connected by tie bars, an open ended trough body secured to said end pieces and tie bars and together with the end pieces forming a trough, end supports secured on and rising from said end pieces of the base, and a series of tubes supported lengthwise over said trough by said end supports.

9. In a heat exchange apparatus, the combination of a series of substantially horizontal tubes, end supports by which said tubes are loosely supported and retained in predetermined relative position one above another, while being left free to expand and contract lengthwise independently, connectors which join said tube end to end in series and which allow independent expansion and contraction of the ends of the tubes relatively to the connectors and a base on which said end supports are secured, said base being provided with a trough beneath said tubes for catching liquid flowing down over the exterior of said tubes.

10. In a heat exchange device, the combination of a bank of tubes over the exterior of which liquid is adapted to flow, and a trough for catching the liquid flowing off of said tubes, said trough being relatively shallow except for a deep pocket at one point in which the liquid is adapted to collect, and a pump inlet connection at the lower portion of said pocket, whereby said connection is kept submerged.

11. In a heat exchange apparatus, the combination of a base provided with a trough, end supports mounted on the ends of said base, a bank of tubes supported one above another lengthwise over said trough by said end supports, side covers at opposite sides of said bank of tubes extending from one to the other of said end supports, and a top cover above said tubes, said trough end supports and side and top covers forming an enclosing chamber for said bank of tubes, and said side and top covers being movable to expose said tubes.

12. In a heat exchange apparatus, the combination of a base, a bank of tubes, stationary end supports by which said tubes are supported over said base, side covers at opposite sides of said bank of tubes extend-

ing from one to the other of said end supports, and a top cover over said bank of tubes, said base, end supports, side and top covers cooperating to form an enclosing chamber for said bank of tubes, and said side and top covers being movable to expose said tubes.

5 13. In a heat exchange apparatus, the combination of a bank of tubes, transverse tracks, side covers movable on said tracks to and from covering positions adjacent opposite sides of said bank of tubes, and a top cover cooperating with said side covers to enclose the upper portion of said bank of tubes.

10 14. In a heat exchange apparatus the combination of a bank of tubes, transverse tracks at the top of said bank of tubes, side covers hung from and movable on said tracks to and from covering positions adjacent opposite sides of said bank of tubes, and a top cover comprising removable sections cooperating with said side covers to enclose the upper portion of said bank of tubes.
